UNITED STATES PATENT OFFICE.

GEORGE S. BARKENTIN, OF NEW BRITAIN, CONNECTICUT, ASSIGNOR TO
P. & F. CORBIN, OF SAME PLACE.

DESIGN FOR THE SURFACE ORNAMENTATION OF BUILDERS' HARDWARE.

SPECIFICATION forming part of Design No. 18,584, dated September 4, 1888.

Application filed July 17, 1888. Serial No. 250,223. Term of patent 7 years.

To all whom it may concern:

Be it known that I, GEORGE S. BARKENTIN, a citizen of the United States, residing at New Britain, in the county of Hartford and State of Connecticut, have invented and produced a new and original Design for the Surface Ornamentation of Borders on Articles of Builders' Hardware, of which the following is a specification, reference being had to the accompanying drawings, forming part thereof.

Figure 1 is a perspective view of a door-knob and escutcheon-plate on which is placed my newly-designed ornamental border. Fig. 2 is a perspective view of a sash-lift having my newly-designed ornamental border thereon, and Fig. 3 is a perspective view of another form of sash-lift having my newly-designed ornamental border thereon.

The invention relates to surface ornamentation of borders on builders' hardware, including the knob, the key-hole, and knob-escutcheons, the face-plate or front of the latch, sash-lifts, hinges, and other articles.

The leading feature of my design consists in the surface ornamentation of a border or band on the prominent faces of articles of builders' hardware—as, for instance, a panel-border or a border for one or more sides of an article—by a barred ground and figures, each consisting of a conventional leaf and scroll arranged in pairs, with the scroll portions of the figures facing each other.

I have herein illustrated my design as applied to a door-knob and escutcheon-plate and two forms of sash-lifts.

In all of the figures, *a* designates leaf and scroll figures, the leaf being formed on one side of each figure and the scroll on the opposite side, which figures are arranged in pairs, with the scroll portions *b* facing each other. The ground or space between these scroll and leaf figures has a series of bars extending lengthwise with the border and transversely to said figures. On the face of the knob A, Fig. 1, the ornamental border extends around in a circle. In the other figures it extends in a straight line or lines. In Fig. 2 it extends along one side only of the sash-lift B; but when applied to a rectangular plate, as the escutcheon-plate C of Fig. 1 or the sash-lift plate D, Fig. 3, the border is extended along four sides.

At the corners of rectangular figures, as in the plate C, Fig. 1, and plate D, Fig. 3, I arrange two scrolls, *c c*, in *V* form, with the point of the *V* toward the outer corner, and upon each side of the scroll are leaflets *d d*.

I claim—

The design for the surface ornamentation of the border on articles of builders' hardware herein shown and described, the same consisting of the series of bars extending lengthwise with the border and the leaf and scroll figures arranged in pairs transversely to said bars, and with the scroll portions *b* facing each other.

GEORGE S. BARKENTIN.
